Primary Examiner — Kimberly Barnes(74) *Attorney, Agent, or Firm* — Banner & Witcoff, Ltd.(57) **CLAIM**

The ornamental design for a permeable paver, as shown and described.

DESCRIPTION

FIG. 1 is a top plan view of a permeable paver showing my new design;

FIG. 2 is a right side elevation view of the permeable paver of FIG. 1;

FIG. 3 is a front elevation view of the permeable paver of FIG. 1;

FIG. 4 is a left side elevation view of the permeable paver of FIG. 1;

FIG. 5 is a rear elevation view of the permeable paver of FIG. 1;

FIG. 6 is an enlarged top plan view of a fastening element that protrudes from the rear and left side of the permeable paver of FIG. 1; and,

FIG. 7 is an enlarged top plan view of a connection element of the permeable paver of FIG. 1.

The broken lines in the drawings depict portions of the permeable paver that form no part of the claimed design.
